(57) **CLAIM**

The ornamental design for a beverage container with lid, as shown and described.

DESCRIPTION

FIG. 1 is a top front isometric view of a beverage container with lid showing the design.

FIG. 2 is a top front isometric view of the beverage container with lid of FIG. 1 in an alternate position.

FIG. 3 is a top front isometric view of the beverage container with lid of FIG. 1 in another alternate position.

FIG. 4 is a top rear isometric view of the beverage container with lid of FIG. 1.

FIG. 5 is front plan view of the beverage container with lid of FIG. 1.

FIG. 6 is a rear plan view of the beverage container with lid of FIG. 1.

FIG. 7 is a left plan view of the beverage container with lid of FIG. 1.

FIG. 8 is a right plan view of the beverage container with lid of FIG. 1.

FIG. 9 is a top plan view of the beverage container with lid of FIG. 1.

FIG. 10 is a bottom plan view of the beverage container with lid of FIG. 1; and,

FIG. 11 is a bottom front isometric view of the beverage container with lid of FIG. 1.

The dashed lines in the drawings illustrate portions of the beverage container that form no part of the claimed design. The shading lines shown in the drawings represent the approximate three-dimensional contour of the claimed design and are not intended to indicate surface decoration.

1 Claim, 10 Drawing Sheets
